US0D1062837S

(12) **United States Design Patent** (10) Patent No.: **US D1,062,837 S**
(45) Date of Patent: ** Feb. 18, 2025

(54) **DIGITAL CAMERA**

(71) Applicant: **FUJIFILM Corporation**, Tokyo (JP)

(72) Inventor: **Masazumi Imai**, Saitama (JP)

(73) Assignee: **FUJIFILM Corporation**, Tokyo (JP)

(**) Term: **15 Years**

(21) Appl. No.: **29/870,012**

(22) Filed: **Jan. 13, 2023**

(30) **Foreign Application Priority Data**

Aug. 18, 2022 (JP) ..... 2022-017558 D

(51) **LOC (15) Cl.** **16-01**

(52) **U.S. Cl.**

USPC **D16/218**; D16/200

(57) **CLAIM**

The ornamental design for a digital camera as shown and described.

DESCRIPTION

FIG. 1 is a top, front, right side perspective view of a digital camera, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown represent portions of the digital camera and form no part of the claimed design.

1 Claim, 7 Drawing Sheets
